UNITED STATES PATENT OFFICE.

JESSIE SAGE ROBERTSON, OF PIEDMONT, CALIFORNIA.

HAND-SPINDLE FOR AND METHOD OF WINDING YARN.

1,330,093.

Specification of Letters Patent. Patented Feb. 10, 1920.

Application filed April 23, 1918. Serial No. 230,334.

To all whom it may concern:

Be it known that I, JESSIE S. ROBERTSON, a citizen of the United States of America, residing at Piedmont, in the county of Oakland and State of California, have invented 5 certain new and useful Improvements in Hand-Spindles for and Methods of Winding Yarn, of which the following is a specification, reference being had therein to the accompanying drawing.

This invention comprises a hand spindle for the winding of wool. While it is of general application, it is contemplated among the objects of the present invention 15 to provide a neat compact spindle upon which wool and the like may be manually wound from a skein or other form of package in such a manner that the material may be formed into a ball, the threads or strands 20 of which are loosely assembled; from which ball, the spindle may be removed after the winding is completed and upon removal of the spindle the lead thread or strand will be withdrawn from the ball to provide for the 25 unwinding thereof from the inside outwardly.

Still a further object is to provide a spindle wherein there is a bore or hollow compartment provided with a removable cap 30 and wherein there may be contained knitting pins, needles, or other implements which it is desirable to have at hand in connection with knitting, darning and the like; wherein there is provided a means for retaining a 35 strand of thread of a ball which is to be wound upon the spindle in such a manner that when the spindle is withdrawn from the ball the thread will be withdrawn with the spindle and constitute a lead for the 40 unwinding of the ball.

Other objects and advantages will in part be apparent and in part be brought out more fully in the description which follows.

A drawing illustrating an embodiment of 45 the invention is hereto attached, the following views being shown:

Figure 1, is a view in sectional elevation of a spindle embodying my invention;

Fig. 2, is a view in elevation diagrammatically indicating a step in the method of 50 winding a ball upon the spindle;

Fig. 3, is a view in perspective showing the completed ball, the spindle being withdrawn therefrom.

55 Referring specifically to the drawing, 1 designates a spindle adapted for the man-

ual winding of wool from a skein or other package. As here shown it comprises a body portion of any suitable form, in the present instance of cylindrical shape and 60 having end portions 2 slightly rounded or tapered. The spindle may be made with an internal bore or compartment 3 having at one end a threaded portion 4 closing the compartment and wherein there may be kept 65 knitting pins, needles or other implements for use in knitting, darning and the like.

The spindle is provided with means for carrying a lead thread so that when a ball is 70 wound thereon and the spindle withdrawn from the ball the lead thread will be withdrawn with the spindle. To this end and as here shown, there is provided a notch 5 in either or both ends of the spindle as a 75 simple means for effecting this result.

The method of winding a ball upon the spindle according to my invention is as follows: The starting thread is inserted in one of the slots in the end of the spindle and folded down on the sides thereof; a plurality of strands or threads are then wound loosely around the spindle and over the folded portions of the thread to constitute a temporary core; the winding may then be continued, the threads being arranged either 80 in approximate parallelism or crossed diagonally to form the complete ball of any desirable size; a few strands of binding thread are then wound around the ball and the loose end of the thread tucked in between 85 the body of the ball and the binder; the spindle is now withdrawn from the ball and carries out with it the end of the thread by means of which the ball may be unwound.

From the foregoing it will be apparent 90 that the spindle which constitutes the subject matter of this invention provides a simple and effective means of accomplishing the objects hereinbefore set forth, and that by means of the method of winding in conjunction with the aforesaid spindle a loosely wound ball is provided wherein the winding 95 may be done from the inside outwardly thus obviating the rolling around of the ball which happens when unwinding is effected 100 from the outside inwardly.

While I have disclosed the invention in the embodiment herein set forth, it will be understood that I do not desire to limit myself to the precise form of this disclosure, 110 as many changes may be made in the construction and application of the spindle

without departing from the spirit of the invention as set forth in the claims.

What I claim is:—

1. A hand spindle including a body portion upon which a ball is windable and having a hollow interior compartment; said body portion having end sections, one of which is provided with a transverse slot therein to receive and retain a portion of the material to be wound on the spindle; and means for permitting access to the compartment within the spindle.
2. A method of hand winding which consists in placing a lead thread upon the body of a spindle intermediate the ends thereof; carrying the thread longitudinally of the spindle across the end of the spindle and securing the thread in a slot in the end of the spindle; continuing the thread to a point

intermediate the ends of the spindle and 20 loosely winding a portion of the thread transversely of the spindle and around the two portions of the lead thread extending longitudinally along the spindle; then tightly winding a ball spirally of the loosely 25 wound transverse winding; winding a binding thread around the outside of the ball; securing the end of the thread to the ball; and withdrawing the spindle axially, whereby the lead thread for rewinding the ball 30 from the inside is withdrawn with the spindle.

In testimony whereof I affix my signature in presence of two witnesses.

JESSIE SAGE ROBERTSON.
